UNITED STATES PATENT OFFICE.

ALBERT KLAIBER, OF BROOKLYN, NEW YORK.

MEDICAL APPARATUS FOR THE TREATMENT OF THE INTESTINES.

Application filed September 4, 1924. Serial No. 735,743.

This invention relates generally to improvements in medical apparatus, and has particular reference to an apparatus employed for the subaqueous irrigation of the intestines.

The invention is designed as an improvement upon the apparatus disclosed in the Brosch et al. United States Patent No. 1,093,251, dated April 14, 1914. In the use of the apparatus shown in said patent, difficulty has been experienced in adjusting the saddle and associated parts to different patients owing to variations in body conformations which, in some instances, cause considerable discomfort during the course of a treatment. Also, it has been found difficult to maintain the highest degree of sanitation while the apparatus of said patent is in use. Furthermore, actual experience and practice has shown that the most efficient results are obtained when the patient is reclining in the bath with the legs straightened out and the upper portion of the body free so that deep and regular breathing may take place. In this connection, when the apparatus of said patent is employed, difficulty is experienced in maintaining the correct position of the saddle on the bottom of the tub and the shoulder straps used to retain the saddle in proper position relative to the body have been found to obstruct proper breathing.

An object of the present invention is to overcome the difficulties above referred to by providing an improved apparatus which is constructed in such manner that the same may be readily adjusted in operative position to eliminate all discomfort to the patient.

Another object is to attach the apparatus to the body of the patient in a manner which will securely maintain the same in operative position and, at the same time, permit the patient to breathe freely and easily so that the maximum benefits to be derived from the use of the apparatus may be obtained.

A further object is to render the apparatus highly sanitary by employing a saddle

construction which will effectively prevent the escape from the apparatus of the flushed out contents of the intestines and also eliminate all danger of infection from said contents.

The above and other objects will appear more clearly from the following detail description when taken in connection with the accompanying drawings, which illustrate preferred embodiments of the inventive idea.

In the drawings:

Figure 1 is a side elevation, partly in section, showing the apparatus in use.

Figure 2 is a vertical longitudinal section of the saddle forming a part of the apparatus.

Figure 3 is a top plan view thereof, partly broken away.

Figure 4 is a fragmentary sectional view showing one form of irrigation tube employed in connection with the invention.

Figure 5 is a similar view of a slightly different form of tube.

Figure 6 is a perspective view of the saddle supporting belt employed; and

Figure 7 is a transverse sectional view therethrough.

The apparatus is particularly designed for use in substantially the same manner as set forth in the above mentioned patent. That is, the treatment with the apparatus involves the seating of the patient within a bath tub 10, or other suitable receptacle with water therein to about the level of the chest and at blood temperature. This is done for the purpose of creating an exterior pressure upon the body of the patient which will, at least in part, counteract the pressure of the fluid injected into the body, thereby avoiding much discomfiture to the patient which oftentimes occurs when administering enemas in the customary manner.

The apparatus forming a part of the present invention is shown as comprising a saddle including a body portion 11 made of any suitable material such as metal and arcuately shaped in longitudinal section so as to conform generally to the contour of the buttocks and other adjacent parts of the

human anatomy. The rear or lower portion of the body 11 carries upon its under surface and adjacent its side edges two supports 12, preferably in the form of suction cups, which engage the bottom of the tub 10 and prevent slipping of the saddle when in use. At a point slightly forward of the supports 12 the underside of the body 11 also has pivoted thereto at 13 one end of an arm 14 capable of moving in a vertical plane and carrying at its free end a third suction cup 15. This latter cup is mounted in a small casing 16 through which the free reduced end of the arm 14 extends and which is pivoted to said arm at 17 to allow the casing to swing in a vertical plane. This is done so that the suction cup 15 will be permitted to at all times engage the bottom of the tub regardless of any adjustment of the arm 14, whereby said cup will assist in maintaining the saddle against accidental displacement in the tub.

The arm 14 is further supported in connection with the saddle by a link 18 pivoted at one end to a discharge duct 19 and carrying a pin 20 at its other end engageable in a longitudinally extending slot 21 formed in the arm 14. The material forming the bottom edge of said slot is provided with a plurality of notches 22 into any one of which the pin 20 may be engaged when adjusting the relative angular relation between the body of the saddle and the arm 14. A wing nut 23 is threaded on the pin and engageable with the arm 14 to secure the link 18 in its adjusted positions. Thus it will be seen that the height of the forward end of the saddle may be regulated in order to comfortably fit the patient when in a sitting posture within the tub.

The body 11 is provided, preferably at a point forwardly of the center thereof, with a discharge opening 24 surrounded by one end of the discharge duct 19 which extends from said opening in an upwardly inclined position. This opening 24 is sufficiently large to surround the anus so that the emitted contents of the intestines will always be discharged thru the duct 19. In order to further insure the proper discharge of waste into the duct 19, a ring or collar 25 is mounted in the end of said duct and extends rearwardly through the opening 24, the free end of said ring being bent to provide a retaining flange 26. This flange is utilized to retain a pad 27, in the form of an air cushion, in position on the body 11, said cushion having an opening which permits the same being readily fitted over and around the ring 25, as clearly shown in Figure 2. The pad 27 is made of rubber or other suitable material and is capable of being inflated, after the patient has assumed a sitting position on the saddle, by means

of a tube 28 extending from the rear of the pad and preferably through openings 29 formed in the body 11. The free end of the tube 28 is provided with a valve 30 for controlling the admission of air into the pad from any suitable source such as a bulb or the like. The pad 27 is of a dimension which will comfortably support the patient and the forward or upper end is extended so that when the pad is inflated said end will effectively cover and close the vagina of a female patient and thereby avoid the possibility of said organ in any way becoming infected by the discharge from the intestines.

Preferably formed integrally with the duct 19 at a point adjacent the saddle body is an extension 31 arranged diagonally with respect to the duct and having communication therewith. In the outer end of said extension there is removably mounted a plug 32 of rubber or the like which supports a feed tube 33 having both longitudinal and rotary movements in said plug. When the tube is mounted in position the inner end thereof terminates at a point centrally of the opening 24 and said inner end is bent laterally and provided upon its extremity, as shown in Figures 2 and 4, with an enlargement or ball 34. Pivoted to this ball, at 35, is the socket end 36 of the irrigation or anal tube 37 having direct communication with said feed tube. By reason of the connection between the tubes 33 and 37, the latter will be capable of a swinging movement about the pivot 35 and in a single plane to the full and dotted line positions shown in Figure 4 or any other intermediate position, the movement of said tube 37 in one direction being limited by engagement of the socket 36 with a pin 38 carried by the ball 34. In the form of connection illustrated in Figure 5, the extremity of the tube 33 has threaded therein a ball member 39 fitted into a socket formed by the sleeve 40 screwed upon the adjacent end of the tube 37. This structure permits of a universal movement of the tube 37 relative to the tube 33. With either of the two constructions just described it will be obvious that sufficient movement will be permitted to the tube 37 to enable the same to be easily inserted into the anus and conform to the contour thereof without injury or discomfort to the patient.

The plug 32 is held in position by means of a cap 41 threaded upon the free end of the extension 31 and engageable with a plate 42 having a head 43 through which the tube 33 extends. After proper longitudinal adjustment of the tube 33 has been obtained to center its lower end with respect to the opening 24, a screw 44 is utilized to secure the plate 42 in position on the tube and the cap 41 is then screwed home upon the ex-

tension 31 until the plate is engaged with the adjacent end of the plug 32.

Means are further provided in connection with the saddle to securely maintain the same in proper position and at the same time permit the patient to breathe freely and deeply without discomfort. This means, as shown, preferably comprises a belt formed of complementary sections generally indicated by the numeral 45 and illustrated in detail in Figures 6 and 7. Each section includes an arcuate plate 46 capable of partially encircling the waist of the patient and said plate is curved transversely, as best shown in Figure 7, to conform to the general contour of the hip. A cover 47 of rubber is provided for each section and the adjacent edges of said cover are connected by a plurality of hooks 48 engageable in eyelets 49 so that the cover may be readily removed if desired. The cover is further provided upon its inner or body engaging side with an air compartment 50 capable of being inflated through the medium of a valved hose 51 after the sections of the belt have been adjusted about the waist, as shown in Figure 1. Adjacent ends of the sections are connected together by the straps or other flexible elements 52 carried by one of the sections and releasably connected to the other section. The forward ends of the sections have attached thereto the straps 53 which extend downwardly for connection to the hooks 54 carried by the upper or forward end of the saddle body, while similar straps 55 at the rear ends of said sections are utilized to connect the rear of the belt to the hooks 56 carried by the lower end of said body.

The medicinal compound or compounds used in effecting a treatment are fed to the tube 33 through a flexible hose 57 one end of which is attached to said tube while the other end is connected to a tank 58 containing the compound, said tank being suspended above the tub 10 in any suitable manner. A valve 59 is utilized to control the flow of the fluid from the tank into said hose.

It sometimes becomes desirable to inject a second medicinal compound of a different nature than that contained in the tank 58. For this purpose a second tank 60 is employed having a branch connection 61 with the hose 57. A valve 62 of any suitable construction may be used to regulate the flow of fluid from the tank 60.

Interposed in the hose 57 is a check valve structure 63 suspended from the tank 58 and utilized to prevent back pressure, sometimes occasioned by actions of the patient when attempting to emit a discharge from the intestines, from forcing any of the waste into either of the tanks 58 or 60 which might otherwise contaminate said tanks and cause infections to subsequent patients. The tanks

58 and 60 are joined to the structure 63 by a short hose 84. This check valve structure is fully shown and described in my co-pending application, Ser. No. 735,744, filed on an even date herewith.

A branch 64 is also connected to the hose 57 through a two-way valve 65 of any well known construction. Said branch carries an air bulb 66 which is utilized for the injection of air into the hose 57 and 75 through the tubes 33 and 37 should the end of the latter tube in the anus become obstructed by discharge from the intestines. When employing this means for clearing the tube 37 the flow of medicine is shut off 80 and the valve 65 turned to close the upper portion of the hose 57.

At any time during the treatment or at its conclusion, it may be desirable to inspect the compound remaining in the intestines 85 which may be discharged through suitable action by the patient into the hose 57 and into another branch 76 communicating with said hose through the valve 67 which, in this instance, is turned to close the portion 90 of the hose above said valve. The branch 76 may empty into a suitable receptacle 68 shown in dotted lines in Figure 1.

When treatment is concluded, the duct 19 may be flushed out and the parts of the patient in the region of the anus cleansed by the injection of a flow of water through the valved pipe 69 extending from and communicating with the interior of said duct as clearly shown in Figure 2.

The invention further includes a drainage apparatus utilized in connection with the saddle and connected to the duct 19. This apparatus is shown and described in detail in the above mentioned co-pending application and will only be briefly referred to herein. It consists of a flexible tube 70 having one end connected to the duct 19 and its other end to one end of a sight tube 71. This latter tube is, in turn, joined to a pipe 72 which telescopes within a second pipe 73 of angular construction. A wing nut 74 is used to secure the pipes 72 and 73 in adjusted positions, the adjustments of these pipes being utilized to vary the effective length thereof in accordance with the height of the patient, it being desirable in all instances that the patient be able to extend his legs as shown in Figure 1. One end of the pipe 73 is extended downwardly and is pivotally connected to the top of a receptacle 75 mounted in the drain opening of the tub 10.

Said end of the pipe 73 is also slideable in a substantially vertical direction in the top of said receptacle so that the pipes 72 and 73 may be raised or lowered as desired. This adjustment is provided for the purpose of positioning the sight tube 71 sufficiently above the surface of the water in the tub 10 to permit the physician or attendant to

observe the contents of the intestines as they are discharged through the duct 19 and into the receptacle 75. The pivotal connection between the pipe 73 and the receptacle 75 is provided so that after the tube 71 is properly located, the flexible tube 70 will not be crimped to such an extent as to obstruct the free passage of matter therethrough.

By the use of the present apparatus, it is possible to inject into the intestines and circulate therethrough as much as six gallons of a compound and this has been repeatedly done without the slightest discomfort to the patient. Furthermore, from the foregoing description it will be obvious that the present apparatus is highly sanitary and most efficient in eliminating all possibility of infection.

What is claimed is:

20 1. In a medical apparatus for the treatment of the intestines, a saddle, a discharge duct extending therefrom, supporting means for said saddle connected to the underside thereof and engageable with the bottom of a receptacle, said supporting means being capable of movements relative to said saddle to vary the position thereof with respect to the body of a patient, means to adjust said supporting means, and an anal tube extending from said duct and saddle and capable of entering the orifice of the anus.

25 2. In a medical apparatus for the treatment of the intestines, a saddle, a discharge duct extending therefrom, a supporting arm carried by and movable relative to said saddle to vary the operative position of the latter, a connection between said duct and arm operable to secure said arm in different adjusted positions, and an anal tube extending from said duct and saddle.

30 3. In a medical apparatus for the subaqueous treatment of the intestines, a saddle, an anal tube extending therefrom, supporting means pivoted to said saddle to permit the latter to assume various angles of inclination relative to the bottom of a receptacle in which the saddle is placed, and means connecting the saddle and supporting means for securing the saddle in its various inclined positions.

35 4. In a medical apparatus for the treatment of the intestines, a saddle, an anal tube extending therefrom, supporting means for said saddle, and means for effecting a relative adjustment between said saddle and supporting means to vary the angle of inclination of said saddle with respect to the bottom of a receptacle on which said saddle rests.

40 5. In a medical apparatus for the subaqueous treatment of the intestines, a saddle adapted to be placed in a water-filled receptacle and supported upon the bottom thereof in various inclined positions relative to said bottom, an anal tube extending

from said saddle, supporting means for said saddle, means for effecting a relative adjustment between said saddle and supporting means to vary the angle of inclination of said saddle, and means for maintaining a fixed position of the saddle relative to said receptacle when a patient is seated on said saddle.

45 6. In a medical apparatus for the treatment of the intestines, a saddle having its supporting surface provided with a discharge opening, an anal tube extending from said opening, and an inflatable pad on said surface and surrounding said opening, said pad, when inflated, forming a seat for the patient and providing a seal about the anus to prevent the escape of waste other than through said discharge opening.

50 7. In a medical apparatus for the treatment of the intestines, a saddle having a discharge opening, an anal tube extending from said opening, and an inflatable pad surrounding said opening and capable, when inflated, of preventing the escape of waste other than through said discharge opening, said pad having a portion adapted to cover the vagina of a female patient and thereby prevent ingress of waste into said organ.

55 8. In a medical apparatus for the treatment of the intestines, a saddle having its supporting surface provided with a discharge opening, an anal tube extending from said opening, a retaining member mounted in said opening, and an inflatable pad on said surface forming a seat for the patient and having a portion engageable between said saddle and retaining member.

60 9. In a medical apparatus for the treatment of the intestines, a saddle capable of resting upon the bottom of a receptacle and providing a seat to permit a patient to assume a reclining position within said receptacle, said saddle having a discharge opening and a discharge duct leading therefrom, a feed tube extending into said duct and having one end capable of disposition within the confines of said opening, and an anal tube pivotally connected to said end of the feed tube and extending from said opening.

65 10. In a medical apparatus for the treatment of the intestines, a saddle having its supporting surface provided with a discharge opening, an anal tube extending through said opening, and means surrounding said discharge opening to provide a seal about the anus of a patient seated on said saddle.

70 11. In a medical apparatus for the treatment of the intestines, a saddle having a discharge opening, a discharge duct communicating with said opening and having an extension, a feed tube mounted for longitudinal movement in said extension to position one end of said tube in proximity to

said discharge opening, and an anal tube carried by said feed tube and having movements relative thereto in a vertical plane.

12. In a medical apparatus for the treatment of the intestines, a saddle having a discharge opening and a discharge duct extending directly from said opening, an anal tube mounted in said opening, and a pipe

extending from said duct and having its inner end arranged adjacent said opening to permit of the injection of a cleansing fluid into said duct in the region of said opening. 10

In testimony whereof I have affixed my signature.

ALBERT KLAIBER.
